UNITED STATES PATENT OFFICE.

LUKE DOYLE, OF BOSTON, MASSACHUSETTS.

DESIGN FOR A WAGON-BODY.

SPECIFICATION forming part of Design No. 21,756, dated August 2, 1892.

Application filed April 7, 1890. Serial No. 346,974. Term of patent 7 years.

To all whom it may concern:

Be it known that I, LUKE DOYLE, a citizen of the United States, residing at Boston, in the county of Suffolk and State of Massachusetts, have invented and produced a new and original Design for a Wagon-Body, of which the following is a specification.

The leading feature of my design consists in a wagon-body of the shape herein shown and described. Said body has vertical sides sustaining a wheel-house of pentagonal form, surmounted by an exterior panel conforming to the shape of the wheel-house. Said panel is designed to be recessed and fitted with slats horizontally laid, said recesses also conforming to the shape of the wheel-house. To the right and left of the latter are exterior elliptical moldings provided with terminals of acorn shape, as illustrated.

Referring to the drawings, A designates the body of the vehicle, and B the pentagonal wheel-house, the surrounding panel being indicated at C and the slats at E. The elliptical panels are indicated at F F, finished with ornate molded edge, as at G G. The terminals of acorn shape are clearly defined at H. The back-rests are shown at I I', attached to the seats J J', while the tail-board is indicated at K.

I claim—
The design for a wagon-body, substantially as herein described and illustrated.

LUKE DOYLE.
